UNITED STATES PATENT OFFICE.

CORNEILIUS KOSTER, OF GRAND RAPIDS, MICHIGAN.

STOCK-SUPPORT FOR BORING-MACHINES.

1,015,497.

Specification of Letters Patent.

Patented Jan. 23, 1912.

Application filed January 22, 1910. Serial No. 539,612.

To all whom it may concern:

Be it known that I, CORNEILIUS KOSTER, a citizen of the United States, residing at Grand Rapids, in the county of Kent and State of Michigan, have invented certain new and useful Improvements in Stock-Supports for Boring-Machines, of which the following is a specification.

My invention relates to improvements in attachments for use on boring machines, and its objects are: First, to provide an attachment for boring machines, and more especially for boring machines for use in boring chair legs, furniture parts &c., with which any desired angle may be readily attained. Second, to provide such an attachment with which the desired degree of angle may be readily attained, and, third, to provide an attachment of the kind named that may be made to readily approach or recede from the bit of the boring machine. I attain these objects by the mechanism illustrated in the accompanying drawing, in which—

Figure 1 is a side elevation of a part of a boring machine with my device in place. Fig. 2 is a plan of the device detached from a boring machine. Fig. 3 is an end elevation of the same. Fig. 4 is a side elevation of the device showing a protractor attached with which to manipulate the stock bed. Fig. 5 is an end view of the device with the stock bed removed to show an index for giving the desired angle to the stock bed arms, and Fig. 6 is a sectional elevation of one of the stock bed arms cut off on the line $\alpha\alpha$ of Fig. 5, and looking to the left from said line.

Similar letters refer to similar parts throughout the several views.

This device consists of a standard A, mounted on, or integral with a base A', which is made to slide freely on the machine bed J, and may be held in proper alignment on said bed, by a rib, as J', or any other suitable device, and by any proper form of securing device, as the set screw H. In the more simple form of this device I place guides, as α , in position so that a bevel square, as G G', may be placed with which to give the desired angle to the adjustable bed B, as indicated in Fig. 2. This bed is pivotally secured to the standard A by means of a central bolt and thumb screw, as indicated at b, and may be provided with a protractor scale, as B', and a fixed hand or index, as b', by means of which the desired

angle of the supporting arms C, to the right or left, may be readily attained, and it is held to the desired position, when attained, by the proper setting of the thumb screw b.

The bed C is pivotally secured to the bed B by means of any available form of bolt and set screw, as indicated at I, in such a manner that it may be readily adjusted to any desired angle from the horizontal, as indicated in Fig. 3, and properly secured to the desired position. With the better form of attachments I prefer that an index, as shown at I' in Fig. 5, be employed to readily determine the exact desired angle of the bed.

The device with which I hold the stock to be bored is, preferably, made with two walls or sides placed at right angles with each other and securely attached or made integral, as indicated at D, and this is pivotally supported at the ends of the arms C' so that

this portion of the attachment may be readily adjusted vertically, as indicated by the dotted lines in Fig. 1, either up or down. With

the cheaper class of machines I provide for holding this angled bed to the desired position by means of a slotted arm, as F, secured to the supporting standard E, as at f, and to the bed D, as at f', but with the better machines I provide a circular brace or indexed protractor, as K, secured to position by a hand screw, as K', passing through the supporting arm C', as indicated in Fig. 4. To facilitate the use of this device I sometimes

place a stop mechanism in the head C in position to act upon the brace K, substantially as indicated in Fig. 6. For this purpose I

find that a device in the form of a brake shoe, as indicated at k, made to engage the edge of the brace K, forced toward the brace

by a suitable spring, as k'', and arranged to be manipulated by a stem and knob, as k', is very effective.

The head k may be made to act upon the edge of the brace as a simple friction shoe, or it may be faced with very fine serrations to engage similar serrations, though when such

serrations are used they must be so very fine as not to interfere with placing the brace at any fraction of a degree of angle desired,

and even an ordinary pin may be made to bear against the edge of the brace for the purpose stated.

The attachment is not designed exclusively for use upon boring machines, the boring machine head L and the bit l being

shown only for the purpose of illustrating the manner of using it with machines of this general class.

- In Fig. 4 I have shown a board, M, supported in the bed D in position to be sawed or shaped, as may be desired, it being understood that the bed D may be placed in any desired position within the scope of the brace K, and the heads B and C may, also, be adjusted to suit the demands of the occasion when using the device upon a miter saw, a shaping machine or other machine where it may be used, the same as with the boring machine.
- 15 N represents a guide secured to the bed D for longitudinal adjustment of the stock, and N' represents a like guide or gage for sidewise measurement, while O represents a handle with which the entire device may be manipulated from the front when in use upon a miter saw, a shaper &c.
- What I claim as new, and desire to secure by Letters Patent of the United States, is:
- 25 1. An attachment for furniture working machinery consisting of a base made to slide freely on a machine table, a standard connected with said base, a bed pivotally connected with said standard for horizontal adjustment, a bed pivotally connected with the side of the first named bed for vertical rotary adjustment, supporting arms on the last mentioned bed, an angled bed pivotally supported at the ends of said arms and arranged for vertical rotary adjustment at right angles with the vertical rotary adjustment of its supporting bed and arms, and means for holding the several beds to the desired position.
- 40 2. In an attachment for furniture machinery, a slidable base, a standard on said base, a bed pivotally secured to the upper surface of said standard for horizontal rotary adjustment, a bed pivotally supported to the side of said first named bed for vertical rotary adjustment at right angles with the movements of the first named bed, supporting arms on said bed, an angled bed pivotally supported on said arms for vertical rotary adjustment at right angles with the supporting bed, gages connected with said angled bed, and means for securing the several beds and gages to the desired positions.

3. In an attachment for furniture machinery, a base slidably secured to the machine bed, a standard on said base, a bed pivotally secured to the upper surface of the standard so that it may be readily adjusted revolubly sidewise, a second bed secured to the side of said bed so that it may be readily made to revolve for vertical adjustment at right angles with the movement of the first named bed, supporting arms extending from said bed, an angled bed pivotally supported on said arms and arranged for rotary adjustment at right angles with said second named bed, an indexed brace arranged to support said angled bed in the desired position.

4. In an attachment for furniture machinery, a base arranged to slide freely on the machine bed, a standard on said base, a bed pivotally secured to the upper surface of the standard and arranged to be given a rotary horizontal adjustment to any desired degree from the horizontal central movement of the base, an index for determining said angle, a bed pivotally secured to the side of said first named bed and arranged to be given vertical rotary adjustment at right angles with the adjustment of the first named bed, and an index to determine the angle of adjustment, arms projecting from said bed, an angled bed pivotally supported on said arms, an indexed segmental brace secured to said bed and connected with the arm to secure said bed to the desired position, and a stop mechanism and a bolt for securing said brace to the desired position.

5. In an attachment for furniture machinery, a base and standard, a bed revolvably adjustable thereon upon a horizontal plane, a second bed pivotally secured to the side of said first named bed and revolvably adjustable thereon upon a vertical plane, arms extending from this bed, a bed pivotally secured to said arms and adjustable upon a vertical plane at right angles with the second named bed, and means for securing said beds to the desired positions and readily determining the desired angles.

Signed at Grand Rapids Michigan January 14, 1909.

CORNEILIUS KOSTER.

In presence of—

I. J. CILLEY,
FRED B. PARKS.
